UNITED STATES PATENT OFFICE.

THOMAS WARNER, OF OREGON CITY, OREGON.

AUTOMATIC MEANS FOR REGULATING PULP-STOCK.

1,225,086.

Specification of Letters Patent.

Patented May 8, 1917.

Application filed May 16, 1916. Serial No. 97,795.

To all whom it may concern:

Be it known that I, THOMAS WARNER, a citizen of the United States, residing at Oregon City, in the county of Clackamas and State of Oregon, have invented certain new and useful Improvements in Automatic Means for Regulating Pulp-Stock, of which the following is a specification.

This invention relates to improvements in pulp stock or stuff regulators whereby the consistency or density of the stock is kept uniform, and while I have described an apparatus which is adapted to insure an even flow of uniform stock to a paper machine so that a paper varying but slightly in weight and texture may be produced, the utility of the device has a much wider scope and can be used to equalize or control the density of the pulp as it comes from the pulp mill or the sulfite mill, or from the mixing tanks where the tank system is in use. In the application of the various types of stuff regulators to a paper machine, the efforts of inventors have been mainly directed toward an automatic stuff gate control in the machine stuff box, regulating by means of an adjustable gate or slide the amount of stock that issues from the box. My device, however, relates more particularly to obtaining a uniform stock before it reaches the machine stuff box, rather than an apparatus to control the flow of the stuff from the box to the machine—it does not attempt to regulate the flow so much as the consistency of the stock itself.

Referring to the drawings:

Figure 1 is a side elevation of my equalizer showing the agitator tank 1 in section;

Fig. 2 is also a side elevation at right angles to Fig. 1, and showing details of the driving mechanism;

Fig. 3 is plan view and Fig. 4 shows in detail the mechanism operating the slide 30 in water control box 20;

Fig. 5 is top view of sliding spool 12, showing split collar 13.

In describing the operation of my apparatus I have assumed that it is to be used in controlling the consistency of the pulp stock delivered to a paper machine. I place the tank 1, Figs. 1 and 2, between the stuff chest and the machine stuff box. Preferably it is situated in the machine room with its overflow at an elevation higher than the machine stuff box, so that the stock will flow by gravity from the equalizer tank to the stuff

box. The stock is pumped from the stuff chest to the bottom of the equalizer tank through pipe 26 and water is admitted at the same time through pipe 24, the mingled mass of pulp and water striking a baffle plate 29 that prevents the stock from spouting up into the middle of the tank and tends to spread the flow of stock evenly on the bottom of the tank. As the pulp rises in the tank it engages the agitator arms 4 and the paddle 2. This paddle is hinged at 25 on the arm 34, which is attached to shaft 5. Its upper end is attached by cable 6 to bell crank 7 mounted on arm 35, which, like arm 34, is firmly affixed to shaft 5. A spring 19 tends to push the upper end of paddle 2 away from arm 34. The cable passes around a sheave 33 at outer end of arm 35. Rods and angle crank could of course be substituted for cable 6, but best results have been obtained with a cable as described. Attached to bell crank 7, Figs. 4 and 5, are jointed rods, 8 and 9, extending upward vertically and parallel with shaft 5, passing through guides 10 and 11. On the top of rod 9 is a socket and ball 16, which latter engages the underside of spool 12. A split collar 13 fits a groove in spool 12 and is attached to a lever 14, supported by fulcrum block 31 and arm 15. At its outer end is attached an arm 21, to which is affixed a vertical slide 30, dividing water box 20 into two sections. This water box 20 has its intake 22 and an outlet 23 on one side of the slide 30 and a bottom outlet 24 on the other side. Outlet 24, Fig. 2, connects with the bottom of tank 1 as shown, just at the stock inlet. Outlet 23 runs to the pit under the wire of the paper machine. Both pipes 22 and 23 are provided with valves so that the flow through each may be regulated. Power is applied by means of the bevel gears 17 and 18, rotating the shaft 5 about seven revolutions per minute. Agitator arms 4, paddle 2, arms 34 and 35, spring 19, rods 8 and 9, all swing around with the shaft 5. Spool 12 does not rotate, but is free to move vertically up and down on the central shaft 5. The apparatus is so adjusted that when there is but slight pressure against the bottom end of paddle 2, the spring 19 will hold it out to its further extension; bell crank 7 and arms 8 and 9 will be held firmly in place so that the spool 12 is up as high as it will go and the slide 30 will be at its lowest position, closing up entirely the opening 32 between the two sec-

tions of water box 20, and thus preventing any water from flowing through pipe 24. Water is then flowing into the intake side of water box 20 and out through pipe 23, the flow being regulated to keep the box nearly full.

Stock that comes from the machine stuff chest varies greatly in consistency and as it gradually fills up the tank 1 and the paddle 10 2 swings through it, a pressure will be brought to bear on the face of the paddle that is proportional to the density of the stock. If it is thin, the pressure will be light; if thick, the pressure will be heavier, 15 varying directly with the specific gravity of the stock. The operation of the apparatus is based upon this phenomena. As the stock flows through pipe 26 and into the tank, pressure is exerted on paddle 2 and if the 20 stock is heavier than desired, of too great a density, depending on the adjustment of the apparatus, the spring 19 will be compressed, the tension will thereby be lessened on cable 6 and the bell crank 7 will be free to respond 25 to any weight on the rods 8 and 9, gravity will cause spool 12 to slide downward on shaft 5, lever 14 will raise the sliding gate 30 in the water box 20 and water will flow through opening 32, Fig. 4, and thence down 30 pipe 24, and thin the too heavy stock in tank 1. When enough water has been admitted to bring the stock to the right degree of 35 consistency, less pressure will be exerted on paddle 2, the compression in spring 19 will tend to overcome the pressure against the paddle, cable 6 will be pulled taut, bringing rods 8 and 9 into elevated position, raising the spool 12 and thus sliding gate 30 will be lowered cutting off somewhat the flow of 40 water through pipe 24. In practice it is well to have some water flowing through pipe 24 and into the stock in the equalizer tank, for almost always the stock comes from the stuff chest of too heavy a consistency 45 and needs thinning. It will take some experimenting to get just the right adjustment for the spring, area of paddle, etc., for the weight of paper desired, but with all the adjustments made, this equalizer will 50 hold the pulp to the correct consistency and a steady flow of uniform stock will pass through pipe 27 to the machine stuff box. It is an easy matter then to set the stuff box 55 gate to regulate the flow of stock to the machine to get the desired weight of sheet required. Thus it will be seen that the stock is fed to the machine stuff box of uniform consistency and that the object of the invention is rather to equalize the stock than to 60 regulate its flow to the machine. This consideration suggests other valuable uses.

Stock from a pulp mill will vary greatly in density, making it difficult for the paper machine tenders to run the sheet to weight when stock is being used directly from the ground wood and sulfite mills. By the use of this equalizer, the stock from the pulp mills can be made of uniform consistency before sending it to the paper mill, a result long desired and whose benefit can hardly be overestimated.

Having thus described my invention, what I claim is,—

1. In a pulp stock regulator, in combination with a tank having a stock inlet and outlet and a water inlet contiguous to the stock inlet, of a central vertical shaft therein carrying three horizontal arms, the lower arm being located at bottom of tank and acting as an agitator, the middle horizontal arm having hinged thereon near its outer extremity an upright arm or paddle, the lower part of which reaches nearly to the bottom of the tank, means for rotating a central shaft, a coil spring attached to the top part of the paddle and the outer end of the top horizontal arm, a cable attached to the top of the paddle arm and to one arm of a bell crank on the top side of the top horizontal arm, two jointed vertical rods parallel with the central shaft, the bottom rod being attached to arm of bell crank, the top arm supporting a sliding spool on the shaft, a lever attached to said spool at one end and carrying a vertical plate at outer end and a box in which said plate slides up and down and divides into two sections, one of the sections being connected to the water inlet in tank.

2. In a pulp stock regulator, in combination with a tank which has a stock inlet and outlet and a water inlet, of a hinged paddle therein whose deflection is proportional to the density of the stock through which it revolves and means for controlling the water supply to the tank dependent upon this deflection of the paddle.

3. In a pulp stock regulator of the character described means for revolving a hinged paddle therein so that its deflection will be proportional to the density of the stock through which it revolves.

4. The method of regulating the consistency of pulp stock which consists of automatically adding water to the stock in proportion to its density as indicated by the deflection of a hinged paddle that revolves through it.

THOMAS WARNER.
